CLEANSING AND SCOURING PAD AND
METHOD

Leonard H. Englund, Chicago, Ill., assignor to
James H. Rhodes & Company, Chicago, Ill., a
corporation of Illinois

Application September 13, 1943, Serial No. 502,121

6 Claims. (Cl. 15—209)

1

This invention relates to the manufacture of cleansing and scouring articles. More particularly, it pertains to an improved cleansing and scouring pad of metallic or non-metallic wool held to an inner core by a plastic composition by a novel method of manufacturing such pads, and the provision of such a pad is a principal object of the invention.

More specifically, it is an object of the invention to provide a cleansing and scouring pad made of a water-resistant material which constitutes a core for the pad covered by a plastic composition which acts as an adhesive and contains a surface active detergent agent, and a binder material which is a rust inhibitor for a covering of steel wool for the core and which also is a means for obtaining optimum pH of water on surfaces being cleansed.

The invention accordingly comprises the several steps and the relation of one or more of such steps with respect to each of the others, and the article possessing the features, properties, and the relation of elements, which are exemplified in the following detailed disclosure, and the scope of the application of which will be indicated in the claims.

For a fuller understanding of the nature and objects of the invention reference should be had to the following detailed description taken in connection with the accompanying drawing, in which:

Fig. 1 is a diagrammatic illustration of a suitable form of apparatus for practicing the present invention;

Fig. 2 is a sectional view taken along the lines 2—2 of Fig. 1 and looking in the direction of the arrows; and

Fig. 3 is a perspective view of a cleansing and scouring pad made in accordance with the principles of the present invention.

Referring more particularly to the drawings, there is indicated at 10 a rotating mandrel mounted upon a standard 11. A water-resistant tape 12 coming off a mill roll 13 on a reel or spool 14 is spirally wound around the mandrel. This tape may consist of any suitable material such as, for example, paper, cotton or similar material, either felted or woven. Such a material can be made water-resistant by a suitable chemical agent, such as, by means of a polyvinyl alcohol or derivatives thereof.

2

Disposed underneath the mandrel 10 is a tank 15 containing a bath of heated plastic composition 16. An applicator roller 17 rotates in the plastic composition and is wiped by a conventional doctor blade 18. The adjustment of the doctor blade will regulate the amount of plastic composition which is applied to the spirally wound web 12 at this point on the mandrel.

The plastic composition 16 essentially preferably contains a surface active detergent agent, such as an alkyl aryl sulfonate, which causes formation of a cleansing lather. Another essential material is a binder which preferably is a rust inhibitor and which has the characteristic of obtaining an optimum pH of water solution on surfaces to be cleansed by the ultimately finished pad when in use and which will maintain a pH range in the water solution on the alkaline side. The exact pH will be determined, of course, by the conditions under which a pad is used, such as, the amount of water, the temperature, the hardness of water, etc. A preferred binding agent of this character is sodium silicate. A scouring agent may also be employed in the nature of pumice stone. A supplemental binding agent may be used which has the characteristic of retarding too rapid or undesirable dissolution of the surface active detergent agent. Cooked starch paste can satisfactorily be used as such a supplemental binding. The starch will also act as a thickening agent and provides desirable viscosity and consistency to the mass of plastic composition in its application to the spirally wound web.

After a desired amount of the plastic composition has been applied to the spirally wound web 12 on the mandrel, a fibrous web of material 19, preferably steel or other metallic wool, running off another mill roll 20 on a reel or spool 21, is oppositely diagonally wound on the mill roll overlying the spirally wound tape containing the plastic composition. The spirally wound tape acts as a member for retaining and reinforcing the fibrous web of steel wool as well as functioning as a means for receiving the plastic composition and in this manner the steel wool is bound to the tape which becomes a core.

As the combined spirally wound web is formed and leaves the end of the mandrel, it is gathered and flattened between counteracting nip rollers

22. The flattened combined web passes over a shear plate 23 where a reciprocating shear knife 24 cuts the web into suitable lengths 25 to form cleansing and scouring pads ready for packaging. Such a pad now consists of a water-resistant material forming a core 26 and a metallic wool outer covering 27 combined with the core by means of a plastic composition 28.

With respect to the plastic composition, it should be noted that an optimum amount of the surface active detergent agent contained therein consists in using approximately two and one-half times the weight of such material as compared with the weight of the steel wool. However, a minimum amount of each of these materials would consist of approximately equal parts by weight.

A cleansing and scouring pad when made by the present method provides an article which is well suited to the purposes for which it is intended. Such a pad possesses many advantages. For example, when in use the plastic composition provides scouring and cleansing agents in conjunction with the steel wool. The pumice stone, if used, augments the scouring action of the steel wool and the pH obtained by the binding material, plus the surface active detergent agent, aids in lending ideal cleansing properties to the pad. The steel wool is also prevented from crumbling because the fibers are held in position by the plastic composition. The binder of sodium silicate inhibits rusting and thus breaking away of the fibers and splintering. A most important feature and advantage is the fact that this novel composition eliminates the use of soap, thus reducing a further tendency to rust as well as reducing a tendency to form sticky and greasy hard water soaps which in conventional pads gum up the steel wool.

It will thus be seen that the objects hereinbefore set forth may readily and efficiently be attained, and since certain changes in carrying out the above method, and certain modifications in the article which embody the invention may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Particularly, it is to be understood that in said claims, ingredients or compounds recited in the singular are intended to include compatible mixtures of such ingredients wherever the sense permits.

Having described my invention, what I claim as new and desire to secure by Letters Patent is:

1. A method of manufacturing cleansing and scouring pads, which comprises forming a web of water-resistant material into a continuous tube, applying a plastic composition containing a surface active detergent to said tube, securing an outer layer of metallic wool to said plastic covered tube, and cutting said tube into suitable lengths.

2. A method of manufacturing cleansing and scouring pads, which comprises forming a web of water-resistant material into a continuous tube, continuously advancing said tube in the direction of its longitudinal axis, applying an adhesive composition containing a surface active

detergent to said tube as it is being advanced in said direction, securing an outer layer of metallic wool to said adhesive covered tube as it is being advanced and simultaneously therewith advancing said layer of metallic wool, and cutting said metallic wool covered tube into suitable lengths.

3. An article of the character described, which comprises a household cleansing and scouring pad constituting a spirally wound sheet of flexible water-resistant fibrous material secured together by an adhesive to provide a tubular core for said pad opened at both ends, said adhesive containing a surface active detergent agent, which adhesive provides a layer of substantial thickness surrounding the outer surface of said core, and a layer of felted metallic wool surrounding said core and secured thereto by said adhesive in which a substantial portion of the strands of said wool are embedded, said pad being capable of repeated use because of the water-resistivity of said core and the binding effect of said adhesive upon said wool whereby the latter resists disintegration during use.

4. An article of the character described, which comprises a household cleansing and scouring pad constituting a spirally wound sheet of flexible water-resistant fibrous material secured together by an adhesive to provide a tubular core for said pad opened at both ends, said adhesive containing a surface active detergent agent and a supplemental binding agent consisting of starch whereby to retard rapid dissolution of said surface active detergent, which adhesive provides a layer of substantial thickness surrounding the outer surface of said core, and a layer of intertwined strands of metallic wool surrounding said core and secured thereto by said adhesive in which a substantial portion of the strands of said wool are embedded, said pad being capable of repeated use because of the water-resistivity of said core and the binding effect of said adhesive upon said wool whereby the latter resists disintegration during use.

5. An article of the character described, which comprises a household cleansing and scouring pad constituting a spirally wound sheet of flexible water-resistant fibrous material secured together by an adhesive to provide a tubular core for said pad opened at both ends, said adhesive containing a surface active detergent agent, which adhesive provides a layer of substantial thickness surrounding the outer surface of said core, a spirally wound web of felted steel wool surrounding said core and secured thereto by said adhesive in which a substantial portion of the strands of said wool are embedded, said pad being capable of repeated use because of the water-resistivity of said core and the binding effect of said adhesive upon said wool whereby the latter resists disintegration during use.

6. An article of the character described, which comprises a household cleansing and scouring pad constituting a spirally wound sheet of flexible water-resistant fibrous material secured to provide a tubular core for said pad opened at both ends, said adhesive comprising an adhesive active detergent agent and a supplemental binding agent consisting of starch whereby to retard rapid dissolution of said surface active detergent, which adhesive provides a layer of substantial thickness surrounding the outer surface of said core, and a spirally wound web of intertwined strands of steel wool surrounding said core and secured thereto by said adhesive in which a substantial portion of

the strands of said wool are embedded, said pad being capable of repeated use because of the water-resistivity of said core and the binding effect of said adhesive upon said wool whereby the latter resists disintegration during use.
